UNITED STATES PATENT OFFICE.

HARRY B. WALKER, OF BROCKTON, MASSACHUSETTS.

SHOE FORM OR LAST.

SPECIFICATION forming part of Letters Patent No. 703,686, dated July 1, 1902.

Application filed September 30, 1901. Serial No. 77,053. (No model.)

To all whom it may concern:

Be it known that I, HARRY B. WALKER, of Brockton, in the county of Plymouth and State of Massachusetts, have invented a new and 5 useful Improvement in Shoe Forms or Lasts, of which the following, taken in connection with the accompanying drawings, is a specification.

My invention relates to improvements in 10 shoe forms or lasts.

It has long been recognized that shoe forms or lasts which will serve to hold distended or in proper smooth filled-out condition the vamp and quarters, or, in other words, the 15 fore part of the uppers, of shoes and yet be capable of easy insertion into and withdrawal from the shoe are much to be desired, and various attempts to provide such a shoe form or last have been essayed, none of which, however, fully satisfy the need by reason of inadequacy or imperfection of adjustment and of complication of the construction of the 20 form or last because of the necessity of employing elements auxiliary or in addition to the last proper. In such prior lasts, furthermore, wherein there is provision for lateral expansion one section is adjustably set into the remaining portion of the last and the set-in section is expanded by auxiliary or additional 25 devices, as before stated. A broken or a non-continuous line of the last is thus formed, making an abrupt break, which is undesirable in the contour. It is of importance in a last intended to serve the purpose 30 accomplished by my invention that the contour-line shall be congruous or continuous—in other words, harmonious in outline as distinguished from a contour-line having abrupt breaks—to conform to the line of the shoe in 35 connection with which it is to be used. These obvious objections to prior constructions are overcome by lasts constructed according to my invention. Another style of last has been proposed in which there is no capacity of lateral 40 adjustability or contractility; but a vertical adjustability is said to be attained by the spring or yielding quality of one part only of the last, which is said to be capable of being depressed toward the other part.

50 Lasts embodying my invention differ therefrom in that both wings of the fore part are resilient and have lateral contractility and

act on a different part of the shoe-upper and in a different manner.

My invention has for its object to provide 55 an improved shoe form or last adapted to hold distended the vamp and quarter portions or fore part of a shoe-upper to present the same in a smooth filled-out condition and adapted to have its fore part contracted or reduced in transverse dimension and to accomplish this by an integral or one-piece shoe form or last of novel construction and formation and without the necessity of auxiliary or additional devices, as heretofore found necessary. 60 65

To the end stated my invention consists, first, in a shoe form or last constructed of a single integral piece of material, comprising a heel part formed integral with a fore part 70 composed of a plurality of separated independent laterally-resilient wings adapted to be brought toward each other more or less, according to necessity, to reduce the transverse dimension of the fore part of the form 75 or last to facilitate its ready insertion into and withdrawal from a shoe and having the capacity when introduced into a shoe (by reason of the inherent resiliency of the wings and their natural tendency to resume their 80 normal free state) to draw away again and fill out the shoe vamp and quarter or fore part of the upper, and, secondly, in such a last, so constructed and possessing such adaptability and capacity, having a construction and formation which facilitates bringing toward each other the separated independent laterally-resilient wings of the fore part of 85 the last to reduce the transverse dimension thereof. 90

It will be observed that my improved last is adapted for use in connection with shoes of lesser or greater width within, say, three of the contemplated or usual market variations in the widths of shoes of a given size or length. 95

My invention is illustrated in the accompanying drawings, in which—

Figure 1 is a side elevation of a form or last, illustrating my invention. Fig. 2 is a plan of the same. Fig. 3 is a longitudinal 100 section upon the line A A of Fig. 2; Fig. 4, a transverse sectional view on the line B B of Figs. 1 and 2, looking toward the toe of the form or last; and Fig. 5 is a transverse ver-

tical sectional view on the line C C of Fig. 3, looking toward the heel portion of the form or last.

In the said drawings the reference character 1 indicates generally the shoe form or last which has a heel portion 1^a, from which extends forwardly and integral therewith or in one piece therewith a plurality of separated independent laterally-resilient wings 1^b, separated by an intervening space 2, which opens at the toe part of the form or last, continues rearwardly toward the heel, and terminates at or near the place where the fore and heel parts of the form or last merge.

15 The laterally-resilient wings 1^b are adapted to be brought toward each other more or less, as may be necessary, in the intervening and separating space 2 to reduce the transverse dimension of the fore part of the form or last 20 and facilitate its ready insertion into and withdrawal from a shoe, each of the wings, as will be obvious from the foregoing description and drawings, being resilient and having the capacity of being made to assume a 25 position different from that assumed when said wings are in their free normal state, whereby the transverse dimension of the form or last is reduced, as aforesaid, and whereby when the form or last is introduced into a 30 shoe the fore part, composed of the independent laterally-resilient wings, has the capacity, by reason of the inherent resiliency of the material and the natural tendency of the wings, to resume their normal free state to 35 draw away again from each other and fill out the shoe vamp and quarter or fore part of the upper.

My improved shoe form or last is capable of filling out the fore part of the upper, whether 40 it be of lesser or greater width, within, say, three of the contemplated or usual market variations in the width of shoes of given size or length. Each wing of the fore part of the shoe form or last acts independently of the 45 other in this endeavor to resume its normal position by springing outwardly laterally until it meets the upper of the shoe, filling out the interior space of the fore part of the shoe and presenting the upper in a smooth filled- 50 out condition.

To facilitate the bringing together of the independent, separated, laterally-resilient wings, I form an enlargement 3 of the separating-space 2 at the crotch thereof. This 55 enlargement is preferably partly circular and facilitates the bringing together of the wings without any undue strain of the material

where the wings merge into the heel portion, and this I regard as of considerable importance.

The heel portion of the last is provided with a socket 4 to receive a suitable handle 5 for use in manipulating the same. This socket may also be used to receive the upper end of a fixed rod or pin to support the form or last 65 in an inverted position while inserting the same into a shoe.

By my invention I provide an improved form or last having a continuous contour-line conforming to the shape of a shoe and which 70 in and of itself inherently, without the necessity of the utilization of auxiliary or additional devices, is capable of being contracted for ready insertion into and withdrawal from the shoe in connection with which it is used 75 and of expanding therein to fill out the fore part of the shoe and present the upper in a smooth filled-out condition.

Having thus described my invention, what I claim is—

1. A shoe form or last having a continuous contour-line, consisting of a heel part and a fore part, made of a single integral piece of material, said fore part consisting of two independent, separated, laterally-resilient wings 85 extending from the heel part and adapted to be brought toward each other to reduce the transverse dimension of the form or last, to facilitate insertion into and withdrawal from the shoe, and to draw away from each other 90 within the shoe to fill out the fore part of the upper thereof, substantially as described.

2. A shoe form or last having a continuous contour-line, consisting of a heel part and a fore part made of a single integral piece of 95 material, said fore part consisting of two independent, laterally-resilient wings extending from the heel part, separated by a space having an enlargement at its crotch, and adapted to be brought toward each other in 100 the intervening space to reduce the transverse dimension of the form or last, to facilitate insertion into and withdrawal from the shoe, and to draw away from each other within 105 the shoe to fill out the fore part of the upper 1105 thereof, substantially as described.

In testimony whereof I have signed my name to this specification, in the presence of two subscribing witnesses, on this 28th day of September, A. D. 1901.

HARRY B. WALKER.
